TO SCHROEDER HEADLIGHT & GENERATOR COMPANY, OF EVANSVILLE, INDIANA,
A CORPORATION OF INDIANA.

FLUID-TURBINE.

1,273,257.

Specification of Letters Patent. Patented July 23, 1918.

Substitute for application Serial No. 9,430, filed February 19, 1915. This application filed October 26, 1916.
Serial No. 127,945.

To all whom it may concern:

Be it known that I, WILLIAM T. MANOGUE, a citizen of the United States of America, and a resident of St. Louis, in the county of 5 St. Louis and State of Missouri, have invented a certain new and useful Improvement in Fluid-Turbines, of which the following is a specification.

This invention relates to turbine-rotors, 10 or, more particularly, to that class of rotors or wheels having a circular row or series of buckets or blades that are secured along the periphery or adjacent the periphery of the carrying disk or wheel where they are adapted to receive the impact or force of the propelling fluid-pressure from a steam or other 15 source nozzle located in convenient position for tangential-delivery of the emitting-jet into the interior of each of the said buckets 20 or blades as they successively advance in the revolutions of the wheel.

The object of the invention is to provide a 25 turbine wheel or rotor with semicircular buckets or blades that have forwardly-projecting side-walls with concave fore-edges and one of such side-walls having at its inner 30 projecting-edge an outwardly-turned hook-formation that is preferably made on the same level as that of the inner-edge of 35 the opposite side-wall and adapted to engage, either a detachable-ring on the inner face of the peripheral-edge of the wheel, or an undercut groove or circumferential annulus made in an inwardly shouldered or 40 thickened periphery of the wheel, and said buckets being adapted to be soldered along their registering and contacting concavo-convex edges to unify all the buckets in circular or continuous ring-form around the 45 wheel near its periphery, whereby they can all be put into and taken from place on the inner face of the wheel simultaneously for repairs, or for substitution, as desired.

The details of structure of the special 50 form of bucket and means of attachment will be fully hereinafter described and particularly defined in the claims that then follow.

In the accompanying sheet of drawings,—

Figure 1 is a fragmentary elevation of the 55 inner face of the wheel showing my improved circular, peripheral row or series of buckets, a few only of the latter being shown broken open and in section, and a detachable

auxiliary-ring being also shown along the inner line of said row of buckets to engage the 55 lower, bent portion of the fastening-hooks of said buckets;

Fig. 2, a radial-section taken on the dotted-line a , a , of Fig. 1, showing one way of securing my said improved buckets in place, 60 (but omitting any elevation of the buckets that would otherwise appear in the background, and, also, omitting the fluid-pressure nozzle that is included in fragmentary 65 form in said Fig. 1);

Fig. 3, a view similar to Fig. 2 but of what might be herein deemed my preferred form of bucket-fastening; and—

Fig. 4, a perspective view showing several 70 of the improved buckets assembled together as they appear in their intended registering-contact for use.

1 indicates the circular body-portion or 75 rotor-disk having an integral lateral, annular peripheral-rib 2 (see Fig. 2), or an annular rib-formation 3 back of or adjacent 80 its periphery (see Fig. 3), and a circular, continuous row or series of propulsion-buckets 4 along or adjacent the said periphery, where they are duly located, as customary, 85 to obtain and develop the greatest percentage of driving-force.

5 indicates the ordinary nozzle for tangentially delivering or directing the fluid-pressure, such as steam or the like, into the 85 said buckets as they successively advance into its discharge-path in the rotation of the wheel.

Each bucket is composed of a semicircular 90 pressure-impinging fore or body-portion 6, side cheeks or walls 7 and 8, and a single, 95 lateral or outwardly-turned hook-formation 9, the latter having its bent portion 10 extending from the side-wall 8 and on the same plane as that of the inner edge of the side-wall 7 of the bucket, as best seen in Figs. 2 and 3, and thereby giving to the tip of the nozzle 5 the greatest lateral play that it, by chance, may have in relation to said inner, fluid-pressure inlet-edge of the bucket 100 and avoiding collision with the hook in case it should project below said inner or lower plane of the bucket.

Each of the side-walls 7 and 8 is provided 105 with a semi-circular or concave edge that is adapted to snugly fit in contact with and be

duly soldered to the convex face of the body-portion 6 of the next succeeding bucket 4 so as to effect tight joints along the entire circular, continuous row or series of buckets.

5 The radial or outer part of each of the hooks 9 of the buckets engages an undercut channel or circumferential groove 10 made in the inner corner or angle of the peripheral-rib 2 (Fig. 2), such groove being somewhat wider than the thickness of the metal in said radial part of the hook whereby less friction and labor are encountered in the insertion of the hooks when placing the buckets along the rim of the wheel, but the 10 said radial part must fit snugly, however, against the face of the outer wall of the groove and thereby obviate any undue vibration, looseness, rattle or lateral play in the fastening-connection. The plane face of the side-wall 8 of each bucket contacts flatly and firmly with that of the lateral, peripheral-rib 2, and the buckets are thus uniformly seated and held in place without the necessity of being otherwise mechanically secured, the aforesaid soldering making tight 15 joints between the buckets and practically unifying all the buckets in a single, composite, continuous ring that is at once strong, rigid and enduring for the turbine purposes desired.

The centrifugal force developed in the speed of the rotor very readily sustains the assembled circular ring of buckets in place, with their hooks in attaching-engagement with the rear-grooved peripheral-rib, but, for an extra safe-guard against any undue collapse of said circular ring of buckets, I provide an auxiliary or emergency ring 11 that is detachably-secured in place 20 on the face of the rotor-disk 1 by means of screws 12, so that its outer face contacts with the transverse part of the hooks and allows no looseness or play that would otherwise only cause rattle and wear.

45 The form of bucket-attachment with the peripheral-rib 2, seen in Figs. 1 and 2, is not a readily applicable or removable one for the reason that the buckets must be first hooked to the said rib 2 and then soldered together, such soldering uniting the buckets so that the continuous series or ring thereof cannot be removed or replaced as a whole, but a hammer or like implement can be used in driving a few of the buckets inwardly toward the wheel center and thereby enabling the ready release of the remainder.

In Fig. 3 I show how the entire circular, continuous row or series of buckets can be applied and removed as a whole or girdle-unit from using position against an outer

angularly-shouldered portion 13 of said lateral annular-rib 3, a detachable-ring 14 being used to simultaneously secure all the buckets in place on the wheel rim, which latter extends beyond that of the form of rim seen in Fig. 2 so as to provide extra material in such extension for the accommodation of transverse screws 15 whose threaded shanks engage the threaded openings made in the thickened outer portion of the said ring 14. In this form of bucket-fastening, on a removable peripheral-ring, an entire set of continuously-connected buckets can be applied or removed bodily from the rotor-disk for repairs or rapid substitution when desired and, if preferred, the ring 14 can be made in a number of segmental parts or sections so that such sections can be removed therefrom without detriment to the buckets 80 and while any of the latter are being repaired or otherwise handled, the ring 14 thus not encumbering the handling of the buckets during such repairs and, also, being adapted for use in connecting another or 85 ready, substitute circular set of assembled buckets without any delay on the form of wheel that I show in Fig. 3. In assembling the buckets, in the form of device seen in Fig. 3, each bucket is hooked in place, one 90 registering directly with the other, along the inner thin edge of the ring 14; then they are duly soldered; and then the ring, carrying the connected buckets, is placed on the shouldered outer edge of the disk 1 for 95 detachable-fastening by means of the screws 15.

I claim:

1. A rotor-wheel composed of a circular disk or body-portion having an integral lateral peripheral rib with an undercut channel or circumferential groove formation constructed along its inner angle, and a circular continuous series of buckets each of which has a single hook formation along its inner or attaching edge and is thereby adapted to be laterally placed into locking-engagement with the said undercut-channel on the rim of the disk.

2. A rotor-bucket comprising a semi-circular pressure-receiving body-portion, side-walls having semicircular edges adapted to register and seat in contact with the body-portion of the next succeeding body-portion in a circular, continuous series of buckets, and a single angular outwardly-turned hook formation projecting from the inner attaching-edge of one of the said side-walls for lateral, ready fastening-engagement in the rotor-wheel.

WILLIAM T. MANOGUE.
